DESIGN FOR A COMBINED WATER AND ICE
BAG

Raymond W. Albright, Akron, Ohio, assignor to
American Anode Inc., Akron, Ohio, a corpora-
tion of Delaware

Application October 6, 1939, Serial No. 87,548

Term of patent 14 years

To all whom it may concern:

Be it known that I, Raymond W. Albright, a citizen of the United States, residing at Akron, in the county of Summit and State of Ohio, have invented a new, original, and ornamental Design for a Combined Water and Ice Bag, of which the following is a specification, reference being had to the accompanying drawing, forming a part thereof.

In the drawing,

Fig. 1 is a rear elevation of a combined water and ice bag embodying my new design;

Fig. 2 is a front elevation of the bag of Fig. 1;
Fig. 3 is a bottom plan view of the bag of Fig. 1;
and

Fig. 4 is a top plan view of the bag of Fig. 1.
I claim:

The ornamental design for a combined water and ice bag, as shown.

RAYMOND W. ALBRIGHT.
